Primary Examiner — Daniel J Domino*Assistant Examiner* — Samina Vieth(74) *Attorney, Agent, or Firm* — Rosenberg, Klein & Lee(57) **CLAIM**

The ornamental design for an antenna, as shown and described.

DESCRIPTION

FIG. 1 is a top perspective view of the antenna;

FIG. 2 is a bottom perspective view of the antenna;

FIG. 3 is a front elevation view of the antenna;

FIG. 4 is a rear elevation view of the antenna;

FIG. 5 is a left elevation view of the antenna;

FIG. 6 is a right elevation view of the antenna;

FIG. 7 is a top elevation view of the antenna; and,

FIG. 8 is a bottom elevation view of the antenna.

The evenly spaced broken lines show portions of the article antenna that form no part of the claimed design.

1 Claim, 8 Drawing Sheets(56)
